PORATION OF PENNSYLVANIA.

ELECTRICAL PROTECTIVE SYSTEM.

Application filed September 29, 1922. Serial No. 591,269.

Our invention relates to electrical protective systems and it has special relation to the prevention of inductive interference in intelligence-transmission circuits, such as 5 telephone and telegraph systems, by reason of the proximity of power-transmission systems.

When power-transmission or railway distribution systems are located in proximity to telephone or other intelligence-transmission circuits, inductive interference tends to occur in the latter circuits, with resultant impairment of service. Such undesirable effects are especially likely to occur when the 10 transmission line is grounded or the railway distribution system becomes short-circuited. By reason of these abnormal conditions, relatively high induced voltages may be so impressed upon the communication circuit as 15 to raise it to a sufficient potential above ground voltage to cause protective equipment to operate. The present types of protectors or protective systems, under the conditions just described, frequently operate in 20 such manner as to impress a material voltage upon the telephone receiver or a repeating coil connected thereto, whereby a severe vibration of the receiver diaphragm is produced, causing bad acoustic disturbance and 25 resulting in a bridging of the protector gaps, thereby absolutely preventing the transmission of intelligible messages.

One object of our invention is to provide 30 a protective system for an intelligence-transmission circuit of such character as to insure substantially simultaneous discharge from the respective sides of the circuit to ground, whereby only a relatively slight acoustic disturbance is experienced in the receiver and 35 no interference with the transmission of messages occurs.

Another object of our invention is to provide 40 a protective system of the character indicated above, whereby the voltage impressed across the terminals of a telephone receiver, for example, is relatively low throughout discharge conditions of the protective means.

Viewed from another angle, it is an 45 object of our invention to provide a protective system of the character in question, wherein a brush discharge to ground is insured under excess-voltage conditions, and the formation of arcs or bridging of protec-

tor gaps, giving rise to severe acoustic disturbances is entirely prevented. 55

Another object of our invention is to provide a protective system for the purpose set forth, wherein balanced brush discharges dissipate excess voltage, and oscillatory arcing conditions are prevented. 60

Other objects of our invention will become evident from the following detailed description, taken in conjunction with the accompanying drawing, wherein 65

Fig. 1 is a diagrammatic view of an intelligence-transmission system that is located in proximity to a power-transmission system, this diagram serving to illustrate one cause of acoustic disturbances in a telephone 70 system.

Fig. 2 is a semi-diagrammatic view of an improved protector device or gap structure that is employed in the protective system 75 illustrated in Fig. 1, and

Figs. 3 to 6, inclusive, are curve charts graphically illustrating certain operating conditions and relations of our electrical protective system in contrast to the systems 80 of the prior art.

Referring to Fig. 1, the power-transmission system here shown comprises a polyphase transmission line 1, for example, which is supplied with energy from one or more suitable locations by means of a corresponding number of alternating-current generators 2, each terminus or distributing point of the line being provided with a suitable delta-star-connected transformer 3, the neutral point of the secondary transformer 85 winding being grounded, as indicated at 4, in accordance with a familiar practice. The secondary transformer winding supplies distribution conductors 5, 6 and 7 with a suitable low voltage, whereby the operation of 90 trains or of industrial establishments may 95 be effected.

The intelligence-transmission system that is shown in Fig. 1 has been chosen by way of example to represent a telephone system of 100 the usual type, although it is to be understood that our invention is not so limited in its application and may be readily applied to the protection of telegraph, signal or other systems of this character. 105

The illustrated telephone system comprises two operating or receiving stations 8 and 9, which are connected by the usual

metallic line circuit 10. The station 8 is diagrammatically represented as comprising a receiver 11 that is connected across the terminals of the circuit and a plurality of improved protective devices or gap structures 12 and 13, which are connected between the respective sides of the telephone circuit and one or more ground connections, as indicated at 14.

10 The other illustrated station 9 is of a similar character, including a receiver 15 and a pair of protective devices 16 and 17 that are connected between the respective sides of the telephone circuit and suitable ground connections, as indicated at 18.

15 It will be understood that the telephone system just described is shown in a simplified form by way of example only, and that all of the additional elements necessary for 20 the usual operation of the telephone or other intelligence-transmission system have been omitted for the sake of simplicity.

25 The improved form of protective device that is preferably employed in connection with our invention is illustrated in Fig. 2. This device is not of our present invention, but is fully set forth and claimed in Patent No. 1,509,497 issued to Joseph Slepian, Serial No. 591,798, filed October 2, 1922, for a 30 spark gap structure, following the broad principles laid down in a prior copending application of Joseph Slepian, Patent No. 1,509,493, Serial No. 535,810, filed February 11, 1922, for lightning arresters, both of these 35 copending applications being assigned to the Westinghouse Electric & Manufacturing Company.

40 The structure shown in Fig. 2 comprises a pair of gaps 12 and 13 each of which is 45 constructed from a pair of relatively high-resistance carbon plates or electrodes 20 and 21 of homogeneous composition, which are spaced apart a relatively short distance, such as three to five mils, by means of an annular spacer or ring 22 of mica, the edges of 50 which ring project beyond the edges of the carbon plates. Suitable clips or holding members 23 may be provided for the respective carbon electrodes, which are connected to one of the line conductors and to ground, respectively, as illustrated in Fig. 1.

55 The protective device just described, by reason of the homogeneous high-resistance material employed in its construction, prevents local heating and the concentration of the discharge, during excess-voltage conditions, at a single point, and thus produces a brush discharge between confronting surfaces. A further characteristic of this 60 type of protective device is the possibility of so constructing and arranging the carbon electrodes as to insure substantially simultaneous discharge of the cooperating pairs of protective devices, such as 12 and 13, as 65 subsequently more fully described. It is be-

lieved that the description just given, together with the operating characteristics hereinafter set forth, will provide a sufficient disclosure of the improved protective device for the purposes of the present specification. 70 For a more complete exposition of the recently evolved theory of operation of this device, reference may be made to the above-noted copending applications of Joseph Slepian. 75

75 The defects and disadvantages of the present protective systems and the method whereby the above-noted protective device overcomes such defects and disadvantages will be described first in connection with 80 the operation of the systems shown in Fig. 1, and then by reference to the various curves that are shown in Figs. 3 to 6, inclusive.

85 It will be assumed that a fault occurs in the distribution system that is shown in Fig. 1, such as a ground at the point 19 on conductor 7. Under this condition, current flows through this fault from the phase conductor 7 to ground and thence to the 90 neutral point of the secondary transformer winding, as indicated by the arrows. The current thus flowing through the earth is distributed in character, but its effect is equivalent to that of a current concentrated 95 at a point several thousand feet below the surface of the earth.

95 The conducting loop carrying the outgoing and returning currents is of such dimensions as to induce a relatively high voltage in any telephone or other intelligence-transmission circuit, such as that illustrated, which runs parallel, or is located in proximity, to the power-transmission system.

100 By reason of the relatively great size of the earth circuit comprising the fault 19, the voltages induced in the two sides of the telephone line circuit 10 are substantially equal. Even if the usual transposition of telephone 105 conductors be employed, the difference in the induced voltages, under the conditions noted, is negligible. Such induced voltages may be sufficiently high to cause the telephone protectors to operate.

110 The operating characteristics of the previously used types of protectors are graphically illustrated in Fig. 3, with ordinates representing voltages and abscissae representing time, under discharge conditions of the protective devices. It will be 115 noted that the characteristics of protective devices of the previously used types are such that, whereas one protector, such as the one corresponding to our protector 12, operates in accordance with curve A, the other protector corresponding to our protector 13, operates in accordance with an entirely different curve B.

120 Upon the occurrence of a high induced voltage, the potential of each protector de- 130

vice rises to a value of approximately 350 volts for a short time. This condition is followed by the concentration of the current at a point, producing first local heating and then an arc. The counter e. m. f. of the protector thereupon drops to 30 to 50 volts and is accompanied by instability of the arc, such that the initiation of the arc on the protector on one side of the circuit tends to quench the arc on the other side, resulting in a high voltage of oscillating character being impressed across the telephone receivers.

In this connection, it should be remembered that the condition for stability of an arc is the concentration thereof at a single point. In other words, it has been found practically impossible for two arcs to operate in parallel relation. For this reason, objectionable oscillation currents were set up in the telephone circuits by the breakdown of the prior types of protective devices.

On the other hand, the characteristics of the brush discharge are entirely different. Such discharge spreads over the confronting gap surfaces (corresponding to parallel operation of the discharge) and no arcing occurs. A non-oscillatory current is thus set up by the operation of protective devices of the improved type, as more fully explained later in connection with Fig. 4.

In other words, protective devices of the previously used types do not discharge uniformly or simultaneously, and do not possess equal discharge impedances or operate under equal discharge voltages. In fact, a relatively high voltage, indicated by the dotted line in Fig. 6 amounting to 300 volts or upwards, is commonly impressed upon the telephone receivers 11 and 15.

A typical operation of the prior protective systems comprises the breakdown of the gaps 12 and 17 before the gaps 13 and 16. In this event, currents corresponding to the above-noted potential of 300 volts or upwards traverse these protectors and the telephone receivers 11 and 15, as indicated by the arrows. Furthermore, an arcing condition is usually set up, being caused by the initial composition and construction and subsequent disintegration of the protective devices. As a result, a very severe acoustic disturbance is always experienced under the conditions described above, which is not only annoying or distressful to any person listening at the time, but is so loud as to absolutely preclude the reception of messages of any character. The resultant permanent bridging of the protector gaps frequently causes the telephone system to become inoperative.

The defects of the present types of protective devices may thus be summarized as non-uniform, non-simultaneous and oscillatory breakdown of the two cooperating protective devices, by reason of the unequal dis-

charge voltages and impedances thereof under breakdown conditions. Moreover, the protector frequently becomes permanently grounded after discharging a relatively small amount of energy by reason of the local heating and subsequent concentration of arcs at a relatively few points.

On the other hand, the operating characteristics, under discharge conditions, of protective devices of the improved type that we employ is indicated in Fig. 4, wherein the curve C represents the operation of protective device 12; for example, and curve D that of protective device 13. It will be noted that, by reason of the substantially uniform, simultaneous and non-oscillatory discharge of the improved protective devices, only a relatively small voltage, corresponding to the vertical distance between curves C and D, is impressed upon the telephone receivers 11 and 15 throughout the discharge condition of the protective means.

In other words, upon the application of a high potential to the protector device, the voltage thereof rises immediately to its discharge voltage, whereupon a brush discharge, but no arcing, takes place. The voltage across the protector does not rise appreciably even though relatively large currents flow through it. Consequently, the protector of the improved type cuts off the peaks of the voltage waves, as indicated in Fig. 6.

By extended experiments, we have found that actually the amount of acoustic disturbances received when protective devices of the improved form are employed is negligible compared with that experienced when the former types of protective devices are employed, so that no annoyance is felt by the listener and no interruption or confusion of the messages being transmitted occurs. In fact, audibility tests indicate a reduction of acoustic disturbance by the use of the present invention in the ratio of 1500 to 1. The sound is less than the ordinary battery "click".

Oscillograph records of the operation of the old and of the improved types of devices show very clearly the oscillatory and non-uniform character of currents set up by the arcing operation of the former, as contrasted with the non-oscillatory and uniform currents caused by the brush-discharge operation of the latter. These records also distinctly show the great reduction in the voltage impressed upon the telephone receivers during such discharge conditions, as compared with the voltage impressed thereupon during the breakdown of the prior protective devices.

The importance and value of the present invention will thus be appreciated, particularly when it is considered that, by the use of the relatively small and inexpensive protective system herein set forth, complicated

and expensive means associated with the power-transmission circuits for preventing inductive interference in telephone lines, may be dispensed with.

5 From Fig. 4 it will be noted that, instead of the local heating and arcing that occur in protective devices of the former type, merely a brush discharge to ground occurs when the improved form of protective device is employed which, if the discharge current is sufficiently large, spreads over the entire surface of the protector, and true arcing, with its deleterious results, is absolutely prevented, as previously explained.

15 The method of spacing the carbon electrodes for each protector device is graphically indicated in Fig. 5, wherein the relation between discharge voltage and the distance of separation is shown. It will be noted that there is a point E corresponding to the minimum discharge voltage. In the construction of the protective device, the spacing of the electrodes in each case is so chosen that, at atmospheric pressure, the 25 discharge voltage is practically the minimum voltage, corresponding to the point E. In other words, the inherent characteristics of the improved protector devices are such that they all possess a minimum discharge voltage and, consequently, under excess voltage 30 conditions, such as are described above, the two cooperating protective devices, such as 12 and 13, will discharge simultaneously and will maintain uniform discharge conditions, as indicated by curves C and D in Fig. 4.

While the curves shown herein relate particularly to the application of a high direct-current voltage to telephone lines, the same results are obtained in the case of the application of alternating currents of relatively high value, although, as will be understood, the contour of the various curves is modified by the alternating-current characteristics of the induced voltage.

45 The above-noted experiments indicate that the protective device shown in Fig. 2 most nearly possesses the ideal operating characteristics of simultaneous and uniform discharge under excess-voltage conditions and non-interference with the normal operation 50 of the telephone circuits. However, it is possible that protector devices or gap structures of other types may be devised or combined to function in accordance with the principles of operation of the present invention. We, therefore, do not consider ourselves restricted to the specific form of device shown in Fig. 2, although, at present, this is the preferred form of protector device for 55 use in the present invention.

We have thus provided a relatively simple

electrical protective system possessing characteristics of substantially simultaneous, uniform and non-oscillatory discharge conditions from each side of a telephone circuit 65 or the like to ground, whenever excess voltages are induced in a telephone line by reason of a fault occurring in a neighboring power-transmission system. The reduction of acoustic disturbance by the use of our invention is very great and, without further expense in connection with the power-transmission line, the transmission of messages is permitted, whereas, with the present type of protective devices, intelligible transmission 70 75 is absolutely prevented and severe acoustic disturbances are experienced.

It should be understood that we do not consider ourselves limited to the particular circuit connections, structural details or arrangement of parts herein set forth, as various modifications thereof may be effected within the spirit and scope of our invention. We desire, therefore, that only such limitations shall be imposed as are indicated in the 80 85 appended claims.

We claim as our invention:

1. The combination with a two-conductor telephone circuit subject to induced voltage disturbances, of an acoustic-shock preventing means comprising two similar autovalve arresters, one of said arresters being connected between each conductor and ground, each of said autovalve arresters being characterized by having two high-resistance 90 plates spaced by a gap of the order of 3 mils in air, the resistivity of said plates being sufficiently high to prevent concentration of the brush discharge into an arc during ordinarily expectable induced-voltage disturbances.

2. The combination with a two-conductor telephone circuit subject to induced voltage disturbances, of an acoustic-shock preventing means comprising apparatus providing two similar discharge gaps of a valve type characterized by operating substantially as an open circuit for voltages below the breakdown voltage and operating, after breakdown, at a voltage of the same order of magnitude as the breakdown voltage throughout the duration of the discharge, whereby sudden drops in voltage during the discharge are avoided, connections of substantially negligible impedance being provided for introducing one of said gaps between each conductor and ground.

In testimony whereof, we have hereunto subscribed our names this 28th day of September, 1922.

CHARLES LE G. FORTESCUE.
ROBERT D. EVANS.
